REFRIGERATOR HYDRATOR AND MOVABLE COVER

Milford J. Schrader, Greenville, Mich., assignor to Gibson Refrigerator Company, Greenville, Mich., a corporation of Michigan

Application March 20, 1951, Serial No. 216,627

6 Claims. (Cl. 312—270)

This invention relates to a refrigerator hydrator and movable cover.

This invention relates to household refrigerators, and especially to a swinging hydrator bin or bins for household refrigerators. The invention is particularly useful in connection with household refrigerators having refrigerated storage space extending substantially from the top to the bottom of the refrigerator and having in the lower rear portion thereof an offset within which the compressor of a well-known refrigerator system is placed. In this preferable construction, the swinging hydrator bin or bins occupy the refrigerated storage space forward of the aforementioned offset and provide therein accessible means for the storage of foodstuffs requiring high humidity refrigeration.

It will be understood that the swinging hydrator bins may be formed in different shapes and may be used in other locations within a household refrigerator and that similar bins may be used in storage cabinets other than refrigerators.

In the operation of the movably-mounted hydrator bins, it is of great importance that the lid or cover of each bin be in place upon the hydrator bin when the same is moved into the refrigerated space. Since the bin often contains bulky articles, it is easy for the lid to be misplaced upon the bins and there is often a failure to properly close the bin. The result is excessive dehydration of the vegetables or other materials in the bins. It also happens that when the bin is wholly removed from the refrigerator cabinet, the lid is left off when the bin is returned to position, thus resulting in excessive dehydration. Further, when the lid is left in position and the bin is swung rearwardly into the refrigerated space, the lid often strikes an object within the space and is tilted or swung out of position to expose the bin therebelow.

An object of this invention is to provide a hydrator bin structure within a refrigerator in which the lid is maintained within the refrigerated space and is automatically placed in position when the bin is swung to closed position. A further object is to provide a hydrator structure for a refrigerator in which the lid for the hydrator bin is moved in a generally vertical plane to permit the removal of the bin in open or exposed condition to provide ready access thereto while upon the return of the bin the lid automatically moves into position for closing the bin. A still further object is to provide a structure in which a lid is supported in the upper portion of the refrigerated space for generally vertical movement, whereby, when the hydrator bin is swung to a position within the space, the lid is raised and then dropped upon the hydrator bin to close the same. A still further object is to provide in such a structure means for limiting the downward movement of the hydrator lid and further for supporting it at an angle to permit the lid to be automatically raised when the hydrator bin is swung inwardly. Yet another object is to equip a hydrator lid with anti-friction means for engaging the hydrator bin to effect

2

raising and lowering of the lid without scratching or marring the same. Yet another object is to provide an improved hydrator bin structure with novel hinging means, permitting the bin to be easily removed for cleaning, etc. and novel lid-supporting means for permitting relative movement in different planes of the hydrator bin and lid. Other specific objects and advantages will appear as the specification proceeds.

The invention is illustrated in an illustrative embodiment by the accompanying drawing, in which—

Figure 1 is a front view in elevation, a portion of the refrigerator near the bottom being broken away to show the hydrator bins; Fig. 2, a side view in elevation, a portion of the refrigerator near the bottom being cut away to expose the side of the hydrator bin; Fig. 3, a perspective view showing the bin, lid therefor and rack or tray thereabove; Fig. 4, a broken side elevational view showing the hydrator bin and means for supporting the lid thereon, a portion of the structure being shown in section; Fig. 5, a view similar to Fig. 4 but showing the bin in its outer or open position; and Fig. 6, a sectional view of the end of the tray opposite the end shown in Fig. 5 and showing the supporting means for that end of the lid.

In the illustration given, 10 designates a refrigerator provided in its bottom or lower portion with an offset wall or partition 11 providing a rear compartment 12. The space in the rear compartment 12 may be occupied by refrigerating machinery, and since such structure is well known, a detailed description is herein believed unnecessary.

Forward of the partition or wall 11 is a refrigerated space 13, as shown best in Fig. 2, and in this space are mounted the hydrator bins 14. Each of the bins is pivotally mounted at its outer forward corner so as to permit the bin to swing along an arcuate path out of and into the refrigerated space. The lower portion of the refrigerator is equipped with a pivot pin 15 which enters a recess 16 in the lower portion of the bin 14, as more clearly shown in Figs. 3 and 4.

Mounted in the refrigerator above the space 13 is a rack or tray 17 which provides a shelf above space 13. The tray 17 is provided with a depending pivot pin 18 which is received within an arcuate slot 19 formed in the corner portion 20 of the bin 14. The slot for receiving the pivot pin 18 is more clearly shown in Fig. 3 and the arcuate formation of the slot is such as to permit the pin to be disengaged from the slot when it is desired to remove the bin bodily for cleaning, etc. In normal operation, the pin lies within the inner portion of the slot and serves as an ordinary pivot to permit inward and outward swinging of the bin.

The bin 14 is provided preferably at its forward side with a horizontally-extending apron 21 and at its rear side with a similar apron extension 22. The bin may be formed of plastic or other suitable material and the structures 21 and 22 may be formed of metal, plastic, or any other suitable material.

Above the bin 14, as shown best in Fig. 3, is a lid or cover 23, which is preferably formed of plastic but may be formed of any other suitable material. The tray is shown equipped with a border portion 24 and with arcuate ribs or track ridges 25 adapted to be engaged by the bin portions 21 and 22 when the lid is being raised, as will be later described.

Integrally formed with the lid 23 at one end is a boss 26 provided with a deep recess 27. The recess 27 of the lid 23 is engaged by a hook or guide member 28, preferably welded at its upper end to the rack 17. The hook serves the double purpose of supporting the lid, as illustrated best in Fig. 5, while at the same time guiding the

lid as it is moved vertically by contact with the hydrator bin 14.

On its opposite side, the lid 23 is provided with a pair of bosses 29 having deep wells 30 therein. The wells 30 are engaged by the legs of a U-shaped member 31 supported centrally by a vertically-extending member 32 which is preferably welded to the rack 17, as shown best in Fig. 6. The spaces 30 and 27 provide sufficient play for the member 28 and the legs of member 31 to permit the lid 23 to swing under off-balance weight to the position illustrated in Fig. 5 when the bin 14 is swung to outer position.

It will be understood that the rack or shelf 17 may be of any suitable construction, being imperforate or perforate, as desired; and the structure is so secured within the refrigerator as to provide supports for the pin 18 and the guide members 28 and 32.

Operation.

In the operation of the structure, when one of the bins 14 is swung outwardly, the bin is exposed at its top so that the vegetables, fruits, etc. therein may be readily removed. The lid or cover 23 remains within the refrigerated space and occupies the tilted position shown in Fig. 5. It is supported in this position by the members 28 and 31. After the vegetables have been removed or replaced within the bin, the housewife pushes the bin rearwardly into the refrigerated space. The hydrator's top portion engages the tilted lid 23 and as it swings in an arcuate plane, travels along the thin ridges 25 of the lid, causing the lid to be slightly raised. When the bin has reached its final position within the refrigerated space, the lid 23 rests squarely across the top of the bin 14, as illustrated best in Fig. 4, and forms a closure therefor. The tilting of the lid 23 is not only effective in providing a cam for raising the lid when the hydrator bin is swung inwardly, but the tilting of the bin further exposes the inner portion of the bin, as shown more clearly in Fig. 5, since the forward portion of the lid swings upwardly to a position immediately under the shelf or rack 17.

While I have shown a hydrator constructed with a specific form of pivot member, it will be understood that the pivoting or means for movably supporting the bin may be varied widely. The bin may be guided for sliding movement, or moved upon horizontal pivots, or constructed in a variety of ways while still raising and lowering the lid for the entrance of the bin into the refrigerated space and for the closure of the lid thereon. I have found that the form of bin illustrated is particularly efficient in that the short arc of movement provided by the pivot structure is highly effective in raising the lid gently and smoothly as the bin swings inwardly and then allowing the lid to seat firmly upon the bin.

While in the foregoing specification, I have set out a specific structure in considerable detail for the purpose of illustrating an embodiment of the invention, it will be understood that the details of structure so shown may be varied widely by those skilled in the art without departing from the spirit of my invention.

I claim:

1. In a cabinet structure providing a storage space, a bin having an open top and being mounted for horizontal swinging movement into and out of said space, and a cover for said bin supported in the upper portion of said space for both vertical and pivotal movement and being supported at off-center points so as to cause said cover to tilt upwardly at its forward end when said bin is swung outwardly, the pivotal axis of said cover being below the

top of said bin when the bin is swung out of said space; said cover being equipped with a plurality of spaced-apart ribs extending generally along the path of movement of said bin, said bin being provided adjacent the open top thereof with border portions extending laterally from the bin and being adapted to engage said ribs during movement of the bin and to form a seal with the edges of the cover when said bin is within said space.

2. The structure of claim 1 in which said bin is supported upon a pivotal axis extending through a corner portion of the bin.

3. In a refrigerator cabinet having a storage space, a bin mounted for horizontal movement into and out of said space, a cover mounted within said space and being adapted to form a sealing closure about said bin when the bin is within said space, shelf means above said cover, and means for supporting said cover upon said shelf, said means comprising a guide member secured to said shelf means and depending therefrom, a boss carried by said cover and being provided with a recess for receiving said guide member therein, a U-shaped member secured to said shelf means and having upwardly-extending legs; and bosses provided by said cover and having wells therein aligned with said legs and receiving the same therein.

4. The structure of claim 3 in which said guide member is arcuate and is equipped with a free end portion extending upwardly and into the recess provided by said first-mentioned boss.

5. The structure of claim 4 in which said second-mentioned bosses are spaced apart and in which said wells extend generally along the path of movement of said bin.

6. In a refrigerator cabinet having a compartment therein, a shelf mounted within said compartment and providing a storage space therebelow, an open-topped bin mounted within said space about a vertically-oriented pivotal axis for swinging movement into and out of said space, a cover mounted within said space and being adapted to rest upon and being supported primarily by said bin when the same is within said space, and means for supporting said cover for pivotal and vertical movement, said means comprising a boss along one side of said cover and providing an upwardly-extending recess elongated transversely of said bin, an arcuate guide member carried by said shelf and having an upwardly-turned end portion receivable within said recess, a pair of bosses provided by said cover and being spaced apart transversely along said bin, said bosses each having an upwardly-extending well therein elongated longitudinally of said bin, and a U-shaped member secured to said shelf and having upwardly-extending legs alignable with and receivable within said wells, said first-mentioned boss and said second-mentioned bosses providing the pivotal axis for said cover and being offset from the center of the cover to cause the forward portion of the cover to tip upwardly when said bin is withdrawn from said space, said guide member and said legs being freely movable vertically respectively within said recess and wells.
